UNITED STATES PATENT OFFICE.

MATTHEW ARNOLD, OF SAN JOSE, CALIFORNIA.

ORE-PULVERIZING MACHINE.

1,035,136.

Specification of Letters Patent. Patented Aug. 13, 1912.

Application filed May 31, 1910. Serial No. 564,324.

To all whom it may concern:

Be it known that I, MATTHEW ARNOLD, a citizen of the United States, residing at San Jose, in the county of Santa Clara and 5 State of California, have invented a new and useful Improvement in Ore-Pulverizing Machines, of which the following is a specification.

It is the object of my invention to so construct an ore pulverizing machine that it may be formed of sufficiently strong material and parts hardened in such a manner to resist the wear of the pulverizing zone to a very small percentage, and also producing 10 pulverized ore of any grain that may be required through the proper adjustment of said machine, and saving more gold, and doing twice the work, with less power and less water than in the old way with stamp mills.

20 My machine is so constructed that any wear that comes to any part is automatically taken up.

The ore before being fed to this machine is first crushed to the size required.

25 The capacity of the machine can be increased by enlargement and by an increase in the length of the stroke.

In reference to the drawings: Figure 1 is a sectional side elevation and Fig. 2 is a 30 transverse sectional view.

Referring to the drawings L is a movable frame or carriage with which the pulverizing wheel, the hoppers, the ore feed chutes, water pipes, etc., move back and forth.

35 B is the main frame and support of my pulverizing machine.

The pulverizing wheel C is made of the hardest and finest carbon steel, and moves back and forth on bar A as frame or carriage L passes backward and forward. It passes off of said bar at each end thereof at the end of each stroke so that the wear of the bar will be distributed equally over its entire length.

45 C² are the roller bearings of wheel C. These roller bearings are made of steel, the proper size and length and hardened and are placed between the two inner circles of wheel C to lessen the friction on wheel C, when the same is at work. Wheel C revolves upon these roller bearings in either direction. I is the main driving shaft and extends through frame B. This shaft is square. There is a pinion A¹, fitted on shaft 50 1. The pinion A¹ is held constantly in mesh

with gear A³ by a yoke bearing A⁴ attached to frame L, and is shown in dotted lines behind gears A¹ and A³. Pinion A¹ engages and drives bevel gear A³ on shaft running through wheel C. The bevel gear on the 60 other end of the last mentioned shaft engages and drives the bevel gear E⁷ at one end of shaft E⁸. At the other end of shaft E⁸ a pinion P² is attached which works in rack P fastened to frame B. 65

Belts on pulleys Z drive gear Z² which engages and drives gear Z¹ attached at one end of main shaft I.

Z are two loose and one tight pulley, and the belts driving the same are one cross and 70 one straight belt. The belts on pulleys Z are shifted by a shift rod, not shown, coming in contact with frame L at the end of each stroke, and the direction of movement of frame L is thereby reversed. 75

R² are the bearings of main shaft 1. The springs on main shaft 1, shown at R Fig. 1, are for the purpose of cushioning frame L at the end of each stroke, and also for the purpose of lessening the friction on shift 80 belts at Z. The weight of frame L is held up to frame B by springs shown at B⁷. The rollers, shown at B³ Fig. 2, are attached to frame L and roll on top of frame B taking the weight of frame L while wheel 85 C is off of bar A at the end of the stroke.

The roller bearings B² are attached to frame L and bear against frame B. They take the upward strain of frame L. A is a longitudinal bar, made of the hardest and 90 finest carbon steel. This bar is the pulverizing track, or surface, and rests upon and is supported by a heavy beam or block A². Block A² is set in and supported by frame B. There is a portion of frame B, corre- 95 sponding in width with bar A, which extends from each end of frame B centrally, and buts up against the ends of block A² and prevents the block A² from being displaced at either end. The top of this por- 100 tion is slightly lower than the upper surface of bar A. To this portion of frame B the levers S², hereinafter described, are fulcrumed, and the stop pins E¹ are also set therein. M are one quarter circle arms, one 105 on each side of wheel C, shown at Fig. 1, and are attached to frame L, one on each end thereof, by fulcrum pins N.

The upper ends of arms M are attached to one end of a rod which runs through a guide 110

attached to frame L. There is a nut on the other end of said rod, and on said rod, between said guide and said nut a spiral spring O is placed for the purpose of adjusting 5 quarter circle arm M. At the lower extremity of arm M is a wheel, shown at 6, which bears against the flanges on either side of wheel C, holding up the weight, and taking up the lost motion of wheel C while off 10 of bar A. E are the ore hoppers, attached to frame L. The ore is fed from hoppers E through sleeve chutes D on to bar A, in front of advancing wheel C by gravitation.

Chutes D are adjustable and can be raised 15 the exact distance from bar A as to correspond with the depth of ore desired to be fed on bar A, and the ore is laid on said bar, and leveled by the bottom of sleeve chutes D as frame L passes forward. There are two 20 ore chutes, one on each side of wheel C, and while the one in front of the advancing wheel is open the other is closed.

The chutes are closed and opened as follows: The sliding lever E² is provided with 25 a projection, running upward, and this projection comes in contact with a pin on shut gate F in front of the advancing wheel, just as the chute reaches the end of bar A, and closes the gate, and lever E² passing forward has reached the top of shift arm S² 30 and has pushed the same over, and the arm of S², shown at Fig. 1, extending centrally at an angle from S², is raised and strikes the pin on the gate on the other side of wheel C as the motion of frame L is reversed and 35 opens the gate. As lever E² leaves the arm S² on the reverse motion of frame L the balance weight BW³ on cord E³, shown passing around rollers E⁴ and attached to 40 the lower end of shift arm S² at E⁵, brings shift arm S² and the lever thereof back to place and in contact with stop pin E¹ set in frame B. Lever E² is attached to frame L and travels back and forth therewith.

45 The balance weights, shown at H⁷ attached to a cord passing over sheaves, shown at H⁸, hold up sleeve chutes D while wheel C is off of bar A. J are guides, connected to frame L, one on each side of wheel C, and 50 pass back and forth with wheel C holding the ore in place, and preventing any ore or dust from escaping from bar A at this point while in operation. These guides are adjustable, being wedge shaped keys held in 55 place by spiral springs K which keep the guides against wheel C. Traveling guides shown at P Fig. 2, are attached to frame L and run along side of bar A and are packed with suitable self adjustable packing to prevent any ore or dust from escaping from bar 60 A until washed off through the screens shown at H.

G are the automatic water supply pipes, one on each side of wheel C, and are placed 65 between wheel C and ore chutes D. These

pipes are attached to frame L and move back and forth therewith. Water is supplied to pipes G by telescope pipes G² fastened to frame L and fulcrumed at the bottom of frame B at G⁵ lengthening and shortening with the motion of frame L.

70 G³ are valves which are opened and shut by rack and pinion, shown at G⁴, constructed in such a manner as to close the valve in front of the advancing wheel C and to open the valve in the rear of the wheel, thereby washing the pulverized ore from bar A.

H are mesh screens through which the ore is washed; H⁵ are plates, or troughs, over which the ore and water passes into chutes H⁶. The circles O, Fig. 2, shown immediately over the lower plates H⁵ are discharges or washouts from frame B, and they open into chutes H⁶.

80 X is a shaft at the lower part of frame B and runs therethrough. Attached to this shaft are the spiral gears SA connecting screws Y, the gears SB, and the clutches V. A clutch V is attached at each end of shaft X and passing upward from these clutches 90 are springs T which work in a sleeve, and at the top of these sleeves are bevel arms, as shown at S, Fig. 1, lying in the jaw of said sleeves. Rollers W at both ends of frame L, and at the lower part thereof, pass 95 with the movement of frame L onto the bevel arms S and press down on springs T and lock clutch V as wheel C leaves bar A. This prevents the turning of shaft X. Shaft X in turning turns the spiral gears 100 SA which are connected to screws Y. Screws Y pass upward and into block or beam A² and are supplied therein with ball bearings R³. These screws are for the purpose of raising bar A, resting on block A², 105 to the proper position for pulverizing, also to take up any wear of the pulverizing surface. The clutches V are locked while wheel C is off of bar A for the apparent reason 110 that the resistance of the weight of frame L, wheel C, etc., is then off bar A, at which time the balance weight and cord BW passing over sheaves X³ would turn the drum SS, thereby turning the gears SB, and the shaft X, and the screws Y, thus raising 115 bar A beyond the proper point if the turning of the shaft was not checked by means of locking clutches V. Arms S are fulcrumed to frame B at their larger ends, and are supported midway of their length 120 upon the tops of shafts 8 of clutch V, and when roller W, on the reverse motion, leaves arms S wheel C is back on bar A and the weight thereof is off of spring T, and the clutch V is released. The balance weight on 125 cord BW turns the drum SS thereby turning the gears SB on shaft X, and the screws Y raise bar A to the adjusted point for the grain of ore desired. Bar A is adjusted by means of an adjustable stop X⁴, on balance 130

weight cord BW, at the proper place thereon, coming in contact with a bracket X¹ shown at Fig. 1, thereby arresting and holding the weight on cord and preventing the further turning of screws Y.

The wear of shaft I is taken up by balance weight BW¹ and balance weight BW² at opposite ends of frame B. The cords attached to these weights pass over sheaves 10 X² and are secured to bearings R², as shown at Fig. 1.

Having thus described my invention, what I claim and desire to secure by Letters Patent is:

15 1. In an ore pulverizing machine, the combination of a main frame, a movable frame adapted to move backward and forward within said main frame, means for imparting said movement to said frame, a longitudinal bar secured within said main frame, a pulverizing wheel movable with said movable frame and rotating on said bar, hoppers attached to said movable frame, feed chutes leading from said hoppers on each side of said wheel, said chutes being adapted to lay ore a required depth 20 on said bar in front of said wheel, a shut gate in each of said chutes, and means for opening the shut gate in front of said wheel when advancing and closing the gate in the 25 rear of said wheel.

2. An ore pulverizing machine comprising a main frame, a longitudinal bar within said frame, means for supporting said bar, a 30 movable frame within said main frame, means for imparting a positive forward and backward movement to the movable frame, a pulverizing wheel carried with said movable frame over said longitudinal bar and 35 rotating thereon, means for imparting and alternating said rotary movement, means for taking up the wear on the longitudinal bar and the pulverizing wheel, ore hoppers attached to and carried by said movable frame, feed chutes opening from said hoppers and adapted to deposit a required 40 depth of ore on said longitudinal bar, means for alternately opening and closing said chutes, and means for washing the 45 pulverized ore from the longitudinal bar in the wake of the pulverizing wheel by water automatically discharged.

3. In an ore pulverizing machine, the combination of a longitudinal bar, a pulverizing wheel adapted to rotate forward and backward on said bar, means for imparting said movement to said wheel, ore feed chutes adapted to deposit ore on said bar in front 50 of said wheel while advancing, a water supply, and connecting means to said water supply terminating over said bar and adapted to wash the pulverized ore from said bar in the wake of the pulverizing wheel.

4. In an ore pulverizing machine, the combination of a longitudinal bar, a pulver-

izing wheel adapted to rotate forward and backward on said bar, ore hoppers over said bar and wheel, a feed chute leading from each of said hoppers to a point immediately above said bar, said chutes being adjustable to lay a required depth of ore on said bar, means for alternately opening and closing said chutes, a water supply, a pipe leading from said supply, discharge pipes connected with said last mentioned pipe and terminating a distance above said bar, valves in said discharge pipes, and means for alternately opening and closing said valves.

5. In an ore pulverizing machine, the combination of a main frame, a longitudinal bar secured in said frame, a movable frame connected to said main frame, a pulverizing wheel movable with said movable frame and adapted to rotate with the movement of said frame forward and backward over said bar, a water supply, a telescope pipe leading therefrom, said pipe being attached to the movable frame and adapted to lengthen and shorten with the movement thereof, a discharge pipe on each side of said wheel leading from said telescope pipe to a point a distance above said bar, valves in said discharge pipes, and means for closing the valve in the discharge pipe in front of the advancing wheel and of opening the valve 95 in the discharge pipe in the wake of said wheel.

6. In an ore pulverizing machine, the combination of a pulverizing wheel, a longitudinal bar on which said wheel travels forward and backward, means for moving said wheel and rotating the same on said bar, ore feed chutes adapted to lay a required depth of ore on said bar in front of said wheel, and means for washing the pulverized ore off of 100 said bar after the said wheel has passed over the same.

7. An ore pulverizing machine, having a main frame, a block secured therein, a longitudinal bar secured to said block, a second frame attached within the main frame and movable parallel with said bar, a pulverizing wheel attached within said second frame and adapted to pass forward and backward on said bar with the movement of 105 the second frame, means for imparting the movement to said second frame, ore hoppers, feed chutes leading from said hoppers to a point a distance above said bar, said chutes being adapted to lay ore on said bar in 110 front of said wheel, means for opening and closing said chutes, a water supply, and means for discharging water therefrom and washing the pulverized ore from said bar after said wheel has passed over the same.

8. In an ore pulverizing machine, the combination of a main frame, a longitudinal bar secured within said frame, a second frame movable forward and backward within said main frame, means for imparting said move-

ment, a pulverizing wheel movable with said second frame and rotating with the movement thereof forward and backward on said bar, means for rotating said wheel, ore hoppers rigidly attached to said movable frame, ore feed chutes leading downward from said hoppers, on each side of said wheel, to a point a distance above said bar, shut gates in each of said chutes, and means for alternately opening and closing said gates.

9. In an ore pulverizing machine, the combination of a main frame, a longitudinal bar secured therein, a movable frame within said main frame, means for imparting a positive forward and backward movement to the movable frame, a pulverizing wheel within said movable frame, means for imparting a rotary motion to said wheel and of reversing said motion with the movement of the movable frame, a telescope pipe, pipes leading therefrom to a point above said bar, valves in said pipes, and means for alternately opening and closing said valves.

10. In an ore pulverizing machine, the combination of a main frame, a longitudinal bar secured therein, a movable frame within said main frame, a shaft extending through said main frame in the upper portion thereof and with bearings therein, a pinion fitted on said shaft with bearings in the movable frame, a pulverizing wheel, the shaft on which it is rigidly mounted, a bevel gear at one end of said shaft, said bevel gear being driven by said pinion, a bevel gear at the opposite end of said shaft, a vertical shaft, a bevel gear at the upper end thereof driven by the last mentioned bevel gear on the shaft of the pulverizing wheel, a pinion at the lower end of said vertical shaft, a rack attached to the main frame in which said pinion works, and means for revolving said first mentioned shaft.

11. In an ore pulverizing machine, the combination of a main frame, a longitudinal bar, a pulverizing wheel adapted to rotate forward and backward on said bar, means for imparting movement to said wheel, a block secured within said main frame upon which said longitudinal bar is attached, a shaft in the lower part of the main frame, screws extending upward into said block, spiral gears connecting said shaft and said screws, a clutch at each end of said shaft, means for operating said clutches, a drum at one end of said main frame, gears connecting said shaft and said drum, a cord passing around said drum, and a balance weight attached to said cord.

12. In an ore pulverizing machine, the combination of a main frame, a block secured therein, a longitudinal bar secured to the upper surface of said block, a frame movable within said main frame, means for imparting a positive forward and backward

movement to said frame, a pulverizing wheel revolvably mounted within said movable frame, means for alternating the rotary movement thereof, a shaft extending through said main frame in the lower portion thereof, screws extending upward from said shaft and passing within said block, and means for operating said shaft and turning said screws.

13. In an ore pulverizing machine, the combination of a main frame, a block therein, a longitudinal bar secured to the upper surface of said block, a shaft in the lower part of said main frame extending therethrough, a plurality of screws extending upward from said shaft, the ends thereof passing into said block, spiral gears connecting said shaft and said screws, a drum, gears connecting said shaft and said drum, a cord passing around said drum, a balance weight attached to said cord, a stop adjustably secured to said cord, a clamp for engaging said stop, a clutch at each end of said shaft, means for operating said clutches, a movable frame within said main frame, a pulverizing wheel movable with said frame adapted to rotate on the upper surface of said bar, and means for imparting said movement to said frame and wheel.

14. In an ore pulverizing machine, the combination of a main frame, a longitudinal bar secured therein, a movable frame within said main frame, means for imparting a positive forward and backward movement to said movable frame, a pulverizing wheel movable with said movable frame and adapted to rotate on said bar and off the same at each end thereof, means for imparting a positive rotary movement to said wheel, flanges on said wheel, one quarter circle arms on each side of said wheel fulcrumed to the movable frame, rods secured to the upper ends of said arms, guides, secured to the movable frame, through which said rods extend, spring means on said rods for adjusting said arms, and a wheel at the lower extremity of each of said arms adapted to bear upward on the flanges of the pulverizing wheel.

15. In an ore pulverizing machine, the combination of a main frame, a second frame movable forward and backward therein, means for imparting said movement to said second frame, a longitudinal bar secured within said main frame, a pulverizing wheel attached within said second frame and revolvably therein, means for revolving said wheel, ore feed chutes adapted to deposit ore on said bar, guides attached to said second frame at each side of the pulverizing wheel, and means for holding said guides in place.

16. In an ore pulverizing machine, the combination of a main frame, a longitudinal bar secured within said frame, a movable

frame within said main frame, means for imparting a forward and backward movement to said movable frame, a pulverizing wheel movable with said movable frame, 5 said wheel being adapted to rotate on said bar and to pass off of said bar at each end thereof, and spring means attached to the upper portion of said movable frame and bearing at the top of said main frame for 10 holding up the weight of the movable frame

while said wheel is off of said bar at each end thereof.

In testimony whereof I have hereunto set my hand in the presence of two subscribing witnesses.

MATTHEW ARNOLD.
